UNITED STATES PATENT OFFICE.

CARL P. HOFF, OF ST. JOSEPH, MISSOURI.

CONCRETE EDGING AND MARKING TOOL COMBINED.

1,273,060.

Specification of Letters Patent. Patented July 16, 1918.

Application filed July 16, 1917. Serial No. 180,900.

To all whom it may concern:

Be it known that I, CARL P. HOFF, a citizen of the United States, residing at St. Joseph, in the county of Buchanan and 5 State of Missouri, have invented certain new and useful Improvements in Concrete Edging and Marking Tools Combined, of which the following is a specification, reference being had therein to the accompanying drawing 10 ing.

My invention relates to improvements in concrete edging and marking tools, combined, the objects of which are, to provide a tool of this class, by the use of which concrete walks, pavements, and the like, can be evenly edged, either laterally, along both edges of a divider, at one time, or longitudinally, along a marginal confining rail; for loosening said divider and rail from the 20 concrete, and for giving the edges of the concrete a smooth, neat form.

Further objects are, to provide adjusting means, whereby the cutting blades can be adjusted to various thicknesses of dividers, 25 and also be so adjusted, as to be adapted to be used as a concrete marking tool. Still further objects are, to provide depth adjusting means, whereby the tool can be adjusted, to compensate for the shrinking in thickness, 30 of the concrete, in such manner, that the edges of the concrete shall be smoothly troweled down, by passage of the tool thereover.

I attain these objects by the devices illustrated in the accompanying drawings, in 35 which:

Figure 1 is a longitudinal section, on the line X X, seen in Fig. 2, looking toward the right. Fig. 2 is a vertical section, on the 40 line Y Y, seen in Fig. 3, looking toward the left. Fig. 3 is a horizontal section, on the line Z Z, seen in Fig. 1, looking downward. Fig. 4 is a front view of the tool, showing the parts in position for use as a longitudinal edger. Fig. 5 is a view, similar to Fig. 4, 45 showing the parts in position for use as a concrete marker, with the gage plates removed. Fig. 6 is a view, similar to Fig. 4, showing the parts in position for use as a concrete groover. Fig. 7 is a front view of 50

one of the various other forms in which the blades may be made.

Referring to Figs. 1, 2 and 3, the tool body 1 has uprights 2 formed therewith, between the upper ends of which, handle 3 is secured. Said body has slots 4, formed therethrough and has channel 5 formed longitudinally in the central portion of its bottom surface. Rider bar 6 is slidably mounted, for vertical movement in said channel. Said 60 bar has the two threaded bolts 6', formed therewith, which latter are passed upward through apertures formed through body 1. Said bolts extend upward through nut apertures 2', which are formed in uprights 2. 65 The upper end portions of said bolts extend into the widened apertures 2'', which are formed in the upper end portions of said uprights. Apertures 2'' are widened for permitting forward and backward movement of the upper end portions of bolts 6'. Nuts 7 and lock nuts 7' are screwed on bolts 6', for adjusting the height of bar 6, and securely holding the same. Said lock nuts have holes 7'' formed therein for reception 75 of one end of a nail or other similar instrument, (not shown,) by which to turn and thereby tighten said lock nut.

Rider bar 6 may be adjusted to a level position, or be so adjusted, that its front end 80 is lower than its rear end, for allowing the described tool to be moved in a slightly inclined position, for purposes hereinafter described.

Said rider bar rides on the top surface 85 of divider 8, (see Fig. 2,) which acts as a straight edge, for guiding said bar and the therewith connected tool, both laterally and vertically.

Since the two bottom plates 9 are alike in 90 construction and operation, but one is described.

Referring to Figs. 2 and 3, bottom plate 9 has the threaded studs 10 formed therewith. Said studs project upward through 95 apertures formed through gage plates 11 and 11', and through their respective slots 4, through body 1. Each one of said studs has a thumb nut 12, screwed thereon, for adjustably securing said bottom plate and 100

said gage plates at various distances from the center of the body 1.

The inner edge of bottom plate 9 is turned and projected downward, forming a cutter 13, which is adapted to cut the concrete 14 from the sides of a divider 8.

The longitudinal edges of said concrete, (of which but one edge is shown,) are formed against border rails 15. The space 10 between said border rails is divided by a plurality of dividers 8, of which but one is shown.

Concrete 14 is mixed and filled into the thus formed spaces, after which, its entire 15 top surface is troweled down.

Cutters 13 are so adjusted, that they loosely fit on one of said dividers. Rider bar 6 is so adjusted that while said bar rests upon the top surface of divider 8, the bottom 20 surfaces of bottom plates 9, press upon the top surface of said concrete. The operator of the tool then grasps handle 3, and thereby moves the described tool toward the right.

This operation cuts said concrete loose 25 from both sides of divider 8, and at the same time, trowels down the adjacent edge portions of the concrete, to the form of bottom plates 9. It has been found in common practice, where but one at a time, of the two 30 edges of the concrete, is cut and troweled, that said edges are generally of uneven height. It will be understood, that by the use of the described tool, said edges are perfectly formed and of even height, and that 35 much time is saved in the operation.

Referring to Fig. 4, one of the bottom plates 9, with its cutter 13, and its gage plates 11 and 11' are removed from body 1, after which the described tool is moved 40 along the longitudinal border rail 15, for cutting concrete 14 loose from said rail, and for troweling into shape, the adjacent edges of said concrete.

Referring to Fig. 5, gage plates 11 and 11' 45 are removed, and the rider bar 6 is lowered by the previously described bar adjusting means, until said bar rests upon concrete 14, for adjusting the depth of cutters 13, in said concrete, after which the described tool is 50 used as a concrete marker.

After placing and securing the parts in the position seen in Fig. 6, with cutters 13 against each other, the tool is used as a concrete groover. When this is done, cutters 13 cut a groove in concrete 14, while the bottom surfaces of bottom plates 9, trowel the corners and the adjacent surfaces of said concrete into the forms of said bottom plates.

In cases where concrete 14 is not much 60 shrunken in thickness, the gage plates 11 and 11' are removed, and bar 6 is adjusted as previously described.

While I have shown and described the

cutters 13 in the foregoing manner, for use as a marker, as seen in Fig. 5, it is evident 65 that said cutters could be made of various shapes, for making a variety of differently shaped marks in the concrete. One of such other forms of cutters is shown in Fig. 7, in which a plurality of cutters 17 are formed 70 with the bottom plate 16. Said cutters, as will be seen, are for making shallower marks of a different form from the ones made by the previously described cutters.

Bottom plate 16 is provided with the 75 threaded studs 10' and the thumb nuts 12', of which but one of each is shown. Said studs are adapted to be used in the same positions as the previously described studs 10.

Having fully described my invention, what 80 I claim as new, and desire to secure by Letters Patent, is:—

1. In a concrete edging and marking tool; a body plate having slots formed therethrough; a pair of bottom plates having 85 screw threaded studs formed therewith, said studs being passed upward through said slots; thumb nuts screwed on said studs for adjustably securing said bottom plates in the same plane on said body plate with a 90 space between them; a concrete cutter formed with each one of the adjacent edges of said bottom plates, said cutters being extended downward from said edges; a pair of uprights formed on the upper surface of said body plate; and a handle secured 95 between the upper ends of said uprights.

2. In a concrete edging and marking tool; a body plate provided with a handle therefor; a pair of bottom plates; adjustable securing means whereby said bottom plates are 100 adjustably secured in the same plane on the bottom of said body plate with a space between them; and a concrete cutter formed with and projecting downward from each 105 one of the adjacent edges of said bottom plates.

3. In a concrete edging and marking tool; a body plate having a channel formed longitudinally in the center of the bottom thereof; a rider bar slidably mounted for vertical movement in said channel; bar adjusting and securing means whereby each end of said bar is independently adjusted and secured at various heights in said channel; a 110 pair of bottom plates; adjustable securing means whereby said bottom plates are adjustably secured in the same plane on the bottom of said body plate; a concrete cutter of blade formation formed on each one of the adjacent edges of said bottom plates and extending downward therefrom; and a handle 115 whereby said body plate and the therewith connected parts are moved over the surface of concrete.

4. In a concrete edging and marking tool;

a body plate provided with a handle therefor; a pair of bottom plates; a plurality of gage plates removably inserted between the bottom of said body plate and said bottom 5 plates; adjustable securing means whereby said pair of bottom plates and said gage plates are adjustably secured on the bottom of said body plate; and a concrete cutter formed on the adjacent edge of each one of

said bottom plates said cutters extending 10 downward therefrom.

In testimony whereof I affix my signature in the presence of two witnesses.

CARL P. HOFF.
